UNITED STATES PATENT OFFICE

LORENZO D. ROBERTS, OF SHAWANO, WISCONSIN

LOCKING DEVICE

Application filed March 9, 1929. Serial No. 345,745.

This invention relates to improvements in calculating machines, a particular purpose being to provide a locking device for certain slides or slide members, and it consists of the constructions, combinations and arrangements herein described and claimed.

Another object of the invention is to provide a rod upon which certain guides are assembled for the purposes of permitting the guides to adjust themselves and to prevent them from either falling over sidewise or out of the machine when the latter is tipped down toward the right in removing or inserting number-slides, and also for the additional important purpose of aiding the locking device in its function.

Other objects and advantages will appear in the following specification, reference being had to the accompanying drawings in which.

Figure 1 is a plan view of the calculating machine illustrating both the improved locking device and guide rod,

Figure 2 is a detail plan view illustrating the locking device moved up to a position wherein it locks the slides and guides in an adjusted position.

Figure 3 is a perspective view of the locking bar,

Figure 4 is a perspective view of one of the coacting guide bars,

Figure 5 is a detail sectional view taken on the line 5—5 of Fig. 1 illustrating the position of the guide rod in reference to the nearest guide bar.

Reference to Patents 917,134, April 6, 1909, 990,779, April 25, 1911, and 1,608,035, November 23, 1926, each granted to Lorenzo D. Roberts will disclose a calculating machine in which certain number-slides appear in alternation with guide bars between which the former are slid in effecting certain number combinations in a calculating operation. Both the number-slides and guide bars are loose, and although this does not spoil given number combinations in the ordinary use of the machine, yet it has developed that to firmly hold both the slides and bars will be of material contribution toward the general efficiency of the machine.

Hence it is herein proposed to provide a locking device for the number-slides and guide bars. Reference is made to the drawings. The base of the calculating machine is designated 10. This comprises a frame or rectangular shallow box, open at the front or face thereof and having an end 11 that in practice is hinged so that it can be let down. A stay bar 12 at the right end of the machine has guide pins 13 that fit in corresponding openings in the end 11, and the stay bar is adjusted in its position by means of set screws 14 which are threaded in the end 11 and bear on the stay bar.

Guides 15 appear in alternation with number-slides 16. The latter are shorter than the former, and the guides comprise narrow strips which properly separate the number-slides and permit individual movement of the latter without danger of disturbing the positions of other slides. This application is not concerned either with the mode of applying certain numbers to the slides or in the manner in which they are operated in performing a calculation. This is disclosed in the foregoing patents.

It is sufficient to say that the number-slides 16 are adjustable in the channels between the guides 15. When the adjustments are arrived at a locking device comprising a bar 17 is pushed in one direction in the frame. One side of the frame has an incline 18. One end of the locking bar has a wedge end 19 that is intended to ride upon the incline 18 and bodily push the entire assembly of guides 15 and number-slides 16 over toward the opposite side of the frame, thus firmly locking all in position.

For the latter purpose the wedge end 19 carries a finger piece 20. It is by this that the locking bar is conveniently slid back and forth. The number-slides have similar finger pieces 21 for the same purpose.

A rod 22, fixed in the base or frame 10 at the left end, has the guides 15 assembled thereupon for the purposes of preventing the guides from dropping over sidewise in the frame and from sliding out when the machine is tilted to the right when changing number-slides.

The guide rod assists the action of the locking bar 17. The latter is of such a length that it practically extends under the entire assembly of slides and guides. Thus 5 when the wedge end 19 is made to ride upon the incline 18 the left extension of the locking bar will advance under the foregoing assembly. By virtue of having the guides 10 15 assembled upon the rod 22, it follows that the guides will move upwardly as a uniform body. Were it not for the guide rod the guides might slightly slip out of position.

It is regarded as a useful mechanical expedient to reinforce the left ends of the 15 guides 15. These, as already stated are thin. The provision of the necessary hole 23 for the reception of the guide rod 22 might leave the adjoining end weak so that it is herein proposed to bind a wire 24 around the end of 20 the guide so as to prevent splitting.

In operation it will be understood that the locking bar 17 will be moved toward the right end of the machine. The various guides 15 and number-slides 16 will then be perfectly 25 loose so as to permit adjustment of the latter to the desired number combinations. When the calculation is completed, the locking bar 17 will be slid to the left, causing the wedge end 19 to ride upon the incline 18 30 and thus lock the guide and slide assembly in position.

While the construction and arrangement 35 of the improved calculating machine and locking device therefor is that of a generally preferred form, obviously modifications and changes may be made without departing from the spirit of the invention or the scope of the claims.

I claim:—

40 1. In a calculating machine, a guide rod, a guide having one end loosely connected with the rod for lateral adaptation in the machine, a number-slide longitudinally adjustable along the guide, a wedge bar situated longitudinally of the guide and number-slide and having a wedge end, and means in the machine upon which the wedge end is movable to shift the wedge bar and number-slide laterally of the machine and the 45 guide along the guide rod.

50 2. A calculating machine comprising a frame including a base which has an inclined portion, a plurality of number-slides and alternate guides arranged in the frame parallel to the base, and a bar movable between the base and nearest guide, said bar having a wedge to ride upon said inclined portion.

55 3. A calculating machine comprising a shallow box having an inclined portion on one side near one end, a guide rod situated transversely of the box near the other end, a plurality of alternate number-slides and guides in the box in parallelism to said side, said guides being slidably mounted on the 60 rod, and a bar movable between said side 65

and the nearest guide, having a wedge to ride upon said inclined portion to shift the guides along the rod hence the number-slides transversely of the box.
